LIGHTNING ARRESTER CONSTRUCTION

Ralph R. Pittman, North Little Rock, Ark.

Application September 20, 1946, Serial No. 698,367

4 Claims. (Cl. 175—30)

1

The invention relates to lightning arresters of the type adapted for the protection of electric power lines and connected apparatus from damaging effects of excessive superimposed voltages, such as may be caused by lightning or switching operations.

The objects of the present invention include (a) the provision of a self-supporting lightning arrester construction in which the structural elements operate electrically to establish a predetermined voltage division among the dielectric elements before sparkover thereof; (b) a construction embodying a series arrangement of a plurality of relatively low voltage arc interrupters to enable their use on high voltage circuits, with the arc interrupters so grouped and coordinated with other supporting elements as to cause advantageous voltage distribution between the arc interrupters; (c) a construction in which the terminal voltage is broken up by certain capacitance relationships and then re-combined in such a manner that the arithmetical sum of the voltages impressed on individual serially-connected arc interrupters may be, prior to sparkover, substantially greater than the voltage measured across the series arrangement; (d) the provision of a voltage-dividing capacitance network in which certain of the capacitances are provided by the inherent capacitance of elements which perform additional useful functions; (e) the provision of a construction embodying a leakage spark gap in series with arc interrupting devices in which the predominate portion of the applied voltage prior to sparkover is expressed across the leakage spark gap, thereby maintaining the conducting elements of the arc interrupting devices at relatively low potential; (f) the provision of means for advantageously increasing that portion of the terminal voltage impressed on each arc interrupter in response to sparkover of the leakage gap to assure formation of relatively long, easily extinguished arcs within the arc interrupters; and (g) the provision of a simple and effective voltage-responsive arc extinguishing structure having a relatively low initial sparkover value, high current-interrupting ability and substantially no impedance drop following sparkover. Other objects and advantages will appear from the description.

High voltage lightning arresters in the present state of the art consist in general of a spark gap structure in series with a current limiting element having resistance for limiting the power follow current to a sufficiently small value to prevent sustained arcing of the spark gap struc-

2

ture following sparkover. The resistance drop attending the passage of the surge current through the resistance element is necessarily impressed on the apparatus the device is intended to protect, resulting in insulation failure if the resistance drop is too great. On the other hand, a low resistance element, for the purpose of limiting the resistance drop to an inconsequential value, may not prevent continued arcing of the gap structure following sparkover, and the entire structure thereby destroyed.

From the above considerations, it is obvious that a high voltage arrester embodying no resistance elements would be an outstanding improvement over the resistance type now generally used. Expulsion type arresters, embodying no resistance, have heretofore been widely used on relatively low voltage circuits, but their use has been uneconomical at higher voltages, for the reason that both dielectric and mechanical strength requirements necessitate a relatively very thick wall if the device has a sufficiently long internal gap to extinguish high voltage follow currents. A plurality of economically designed low-voltage expulsion units arranged in series end-to-end relation, with the necessary leakage gap, and with nothing more, requires too high initial sparkover to provide the desired degree of protection. If however, the voltage impressed across the arrester is subdivided, and the gaps of the arc interrupters subjected to certain peculiarly added combinations of the component voltages, it is possible to provide the desired low initial sparkover voltage, and extinguish high follow current arcs without the use of an undesirable current limiting resistor. The manner in which this is accomplished will be clear from the following description of the invention.

Fig. 1 of the drawing is an elevation of an embodiment of the invention shown partly in section; Figs. 2 and 3 are circuit diagrams showing advantageous voltage relationships of the dielectric elements; Fig. 4 is an elevational view illustrating an embodiment of the invention for use with higher voltage circuits; and Fig. 5 is an elevational view of another embodiment of the invention.

Referring first to Fig. 1, the mounting base 32, of conducting material, has mounted thereon insulating means in the form of an upstanding capacitor 28 and an upwardly extending spool of conducting material 26. A flat conducting member 22 is rigidly secured to the top plate of the capacitor 28, by means of the cap screw 19, the respective ends extending outwardly to provide

space for mounting thereon first and second arc interrupters 17, the latter being rigidly fastened to the conducting member 22 by means of the cap screws 19, and extending upwardly therefrom in spaced parallel relationship. Also extending upwardly in spaced parallel relationship with the previously mentioned arc interrupters 17, is a third arc interrupter 17, carried on the spool 26.

A flat conducting member 21 extends laterally across and rigidly joins the respective upper ends of the second and third arc interrupters 17, being fastened thereto by means of the cap screws 16, and being provided with a portion extending outwardly toward the first arc interrupter 17, and thence downwardly parallel thereto. Similarly, 15 the conducting member 18 is rigidly secured to the top of the first arc interrupter 17, and provided with a portion extending outwardly toward the second arc interrupter 17, and thence downwardly parallel thereto. An insulator in the form of another capacitor 28 bridges the space between the respective down-turned portions of the conducting members 18 and 21, being rigidly fastened thereto by means of the cap screws 19, and thereby holding the first and second interrupters 17 in parallel relationship.

To prevent passage of damaging leakage current through the interrupters 17, a leakage spark gap is provided in series therewith. One electrode of the leakage gap is fastened at the upper end of the first interrupter 17 by means of the cap screw 16, extending first upwardly and thence laterally therefrom in spaced relationship with the second spark gap electrode 12, the latter being mounted at the upper end of the insulator 14 by means of the cap screw 13. The lower end of the insulator 14 is secured to the flat conducting member 21 by means of the cap screw 13. A first terminal 11 is formed on an outwardly extending portion of the electrode 12, a line conductor 10 being shown connected thereto, and the other or second terminal 24, connected to the conductor 25 which may be a grounded conductor, is formed on the outwardly extending portion of the conducting member 23, the latter being disposed between the lower end of the third arc interrupter 17 and the top of the spool 26.

The arc interrupter 17 illustrated in Fig. 1 is a voltage-limiting and arc extinguishing gap discharge device similar to that shown and described in more detail in Pittman Patent No. 2,164,729, dated July 4, 1939. As here shown, the arc interrupter includes the outer tubular insulator 28, provided with the terminal member electrodes 27 and 31, and containing the eccentrically disposed filler 29. The lower electrode 31 is provided with a conductively-related upwardly extending extension 30, the members being so arranged and related that the weakest sparkover path through the device is along the line of abutment of the filler 29 with the inner surface of the tubular insulator 28, and between the upper end of the extension 30 and the upper terminal member 27. Following sparkover, any ensuing arc is driven around the filler 29, being thereby concurrently moved laterally and elongated, as so cooled to effect extinguishment. The gaseous products attending the arc are discharged in a horizontal direction through the vent 33 in the lower terminal member, and the device is economically constructed when the tubular insulator 28 and the filler 29 are formed of a gas-evolving material, such as hard fiber.

To facilitate a clear understanding of the importance of the capacitance relationships desir-

able in the construction of the invention, definite practical values of capacitance have been assigned to the dielectric members of the structure in Figs. 1 and 2, and the resultant corresponding voltage relationships indicated as a percentage of a terminal voltage applied across the terminals of the arrester. Based on the principle that the voltage across capacitors in series divides inversely between the relative capacitances, it will be evident that a predominate portion of the terminal voltage prior to sparkover will appear across the spark gap between the electrodes 15 and 12 if the capacitance of the insulator 14 (here indicated as 7 mmf.) is small in comparison with the equivalent capacitance formed by all of the other dielectric members. This is the preferred arrangement, for the reason that corona damage is avoided in the arc interrupters by holding the conducting members thereof near ground potential.

Not only is it desirable that the voltage impressed on the individual arc interrupters be low prior to flashover, but it is also desirable that this voltage be high in response to sparkover of the spark gap, and the values stated in Fig. 2 appear following sparkover of the spark gap as the result of the magnitude and manner of combination of the capacitance values designated in Fig. 1. To accomplish this result, it will be evident from inspection that relatively small capacitances of the arc interrupters in the circuit arrangement of the invention are desirable. Since such devices inherently have small capacitance, they may be used without modification in the construction.

It will be observed in the particular arrangement diagrammed that the voltages appearing across the first, second and third interrupters are numerically 79% E, 62% E and 83% E, making in arithmetical sum 224% E, compared to a terminal voltage of 100% E. This result is obtained by the connection of a first relatively large capacitor in shunt with the series arrangement of the first and second arc interrupters, and the connection of a second relatively large capacitor in shunt with the series arrangement of the second and third arc interrupters, by which circuit arrangement the voltage across the first arc interrupter is the sum of the voltage across the first capacitor and the second arc interrupter, the voltage across the second arc interrupter the difference between the terminal voltage and the sum of the voltages across the first and second capacitors, and the voltage across the third arc interrupter the sum of the voltages across the second arc interrupter and the second capacitor. Or viewed in another way, the voltage drop of the relatively small capacitance formed by the normally insulated conducting elements of the middle or intermediate arrester is common to the invention to all of the interrupters. Three interrupters is the minimum number which can be combined in this manner, and of course any odd number greater than three may be built up around a central group of three so that the voltage drop of the middle unit will be common to all of the interrupters on each side thereof.

It is obvious from an inspection of Fig. 2 that all three arc interrupters may be made to sparkover substantially concurrently by appropriate electrode spacings. This, however, is not essential, because if any one of the series arrangement of the three interrupters sparks over, the remaining two have impressed thereon the total voltage, and follow quickly before the terminal voltage is raised any appreciable degree, so that

for practical purposes, identical arc interrupters may be used. In any event, it will be apparent that the two important considerations are (1) that the arc interrupters in series be included in the preferential sparkover path and (2) that the overall sparkover of spark gap plus arc interrupters be sufficiently low to protect associated apparatus. In accordance with the above considerations the preferential sparkover path from the terminal 11 to the terminal 24 is from the spark gap electrode 12 to the spark gap electrode 15, thence downwardly through the first arc interrupter 17 to the conducting member 22, thence upwardly through the second arc interrupter 17 to the conducting member 21, and thence downwardly through the third arc interrupter 17 to the conducting member 23 and the terminal 24.

A principal advantage of dividing the terminal voltage and recombining components of the divided voltage to obtain more than 33 1/3% of the terminal voltage on each one of three arc interrupters in series, resides in the fact that the protective level of the interrupters may be correspondingly lowered, thus providing a correspondingly greater margin of protection without any shortening of length of arc path. If, for example, three 9 kv. arc interrupters, each having a 50 kv., 1 1/2-40 ms. positive wave sparkover, are connected directly in end-to-end series relation have a total sparkover value of 150 kv., it is possible to arrange the interrupters under the conditions of Fig. 2 so that a series arrangement will sparkover with a terminal voltage of only roughly 50/0.8 kv. or 62.5 kv.

Through utilization of the features of construction described above, it is possible to stack the interrupters in groups of three, if desired, and such a construction is shown at Fig. 4 of the drawing. In this construction, an insulator 34, of small capacitance, supports the spark gap electrode 35, which extends in spaced relationship with the other spark gap electrode 36, the latter being mounted on and electrically connected to the upper terminal member of the first arc interrupter 17. The direction of current traversing the series arrangement forming the preferential discharge path from the line terminal 10 to the ground terminal 25 is same as that in the construction previously described, i. e., downward through the outside interrupters, and upward through the middle or intermediate interrupter. In this structure, the capacitors not only serve to control voltage division and as structural supporting members, but also to vertically space the interrupters so that the gas vents are spaced sufficiently to avoid mixing of the gas from two or more vents. The conducting gas discharged from each vent is at a potential different from that discharged from any other, and for successful operation, the gases must be isolated in space until cooled to a reduced conductivity by their passage through the air.

In the above description, only capacitance relationships have been regarded in determining the various voltage components. The resistance drop has not been included, although it may if desired be made an important part of the impedance drop, for the reason that it is clear that the capacitance of the dielectric elements incorporated in the invention may vary widely from the specific values stated, since it is relationship therebetween which is the dominating consideration, rather than the absolute values. In addition, the current passing through a capacitor is

a function of the rate of change of voltage with time, rather than the magnitude, and it is the rapidly increasing voltages which are most dangerous to apparatus, and I therefore have discussed herein only capacitance relationships in obtaining the desired voltage combinations.

In certain respects the present invention is similar to that described in my copending application Serial No. 666,902 filed May 3, 1946, now 10 Patent No. 2,427,975, the similarity being found in the circuit diagram rather than in the structure.

The embodiments specifically described herein readily suggest other constructions falling within 15 the scope of the invention, and it is therefore intended that this description of the invention will be regarded as illustrative rather than limiting.

I claim, as my invention:

1. A lightning arrester construction comprising spaced line and ground terminals, means providing a preferential discharge path from the line terminal to the ground terminal, said means including first, second and third arc interrupters disposed in spaced parallel relationship, each of 25 said interrupters including an elongate upstanding tubular insulator, normally insulated conducting terminal members mounted at the respective ends of each insulator, and structural means for causing sparkover between said terminal members to occur within said insulator, conducting means serially connecting said interrupters, said conducting means including a first laterally extending conducting member rigidly secured to the respective lower terminal members 30 of said first and second interrupters and a second laterally extending conducting member rigidly secured to the upper terminal members of said second and third interrupters, an insulator rigidly mounted on said second conducting member 35 upon which said line terminal is carried, elements constituting a spark gap between said line terminal and the terminal member at the upper end of said first interrupter, and means for impressing a predominate portion of the voltage expressed between said spaced terminals across said 40 spark gap prior to sparkover thereof, said means including a first capacitor shunting the series arrangement of said first and second arc interrupters and a second capacitor shunting the series arrangement of said second and third arc interrupters.

2. An arrester construction in accordance with claim 1, characterized by the capacitance of each of the capacitors being greater than the inherent capacitance of either said insulator or any of said arc interrupters.

3. A lightning arrester construction comprising spaced line and ground terminals, means providing a preferential discharge path from the line 60 terminal to the ground terminal, said means including first, second and third arc interrupters disposed in spaced parallel relationship, each of said interrupters including an elongate upstanding tubular insulator, normally insulated conducting terminal members mounted at the respective ends of each insulator, and structural means for causing sparkover between said terminal members to occur within said insulator, conducting means serially connecting said interrupters, said 65 conducting means including a first laterally extending conducting member rigidly secured to the respective lower terminal members of said first and second interrupters and a second laterally extending conducting member rigidly secured to the upper terminal members of said second and
